UNITED STATES PATENT OFFICE.

CHARLES L. SULLIVAN, OF MOUNDSVILLE, WEST VIRGINIA, ASSIGNOR TO FOSTORIA
GLASS COMPANY, OF MOUNDSVILLE, WEST VIRGINIA, A CORPORATION OF WEST
VIRGINIA.

DESIGN FOR AN ARTICLE OF MANUFACTURE.

52,413.

Specification for Design.

Patented Sept. 10, 1918.

Application filed December 31, 1917. Serial No. 209,799. Term of patent 3½ years.

To all whom it may concern:

Be it known that I, CHARLES L. SULLIVAN, a citizen of the United States of America, and resident of Moundsville, county of Marshall, and State of West Virginia, have invented an original and ornamental Design for an Article of Manufacture, of which the following is a specification, reference being had to the accompanying drawings, in which—

The single figure is a view in side elevation of a drinking glass illustrating the new design.

Copies of this patent may be obtained for five cents each, by addressing the "Commissioner of Patents, Washington, D. C."

The design, which consists of the configuration shown, may be applied to drinking glasses, dishes, vases and other glass articles.

I claim—

The ornamental design for an article of manufacture, substantially as shown.

CHARLES L. SULLIVAN.
